UNITED STATES PATENT OFFICE.

JOHN L. PASCAL, OF POCOHONTAS, IOWA.

ROAD-DRAG.

1,290,332.

Specification of Letters Patent.

Patented Jan. 7, 1919.

Application filed March 12, 1918. Serial No. 221,885.

To all whom it may concern:

Be it known that I, JOHN L. PASCAL, a citizen of the United States of America, and resident of Pocahontas, Pocahontas county, Iowa, have invented a new and useful Road-Drag, of which the following is a specification.

The object of this invention is to provide an improved construction for road drags.

A further object of this invention is to provide an improved construction for a drag adapted for the treatment of the entire width of a roadway in and during a single passage.

A further object of this invention is to provide an improved construction for means for leveling and smoothing a traction surface.

A further object of this invention is to provide means for eliminating pockets, hollows and bumps in a traction surface.

A further object of this invention is to provide an improved construction and arrangement for independent and connectible drag sections.

A further object of this invention is to provide an improved sectional construction for a road drag.

A further object of this invention is to provide an improved construction for a flexible road drag.

A further object of this invention is to provide an improved construction whereby drag sections formed with inclined or obliquely arranged longitudinal members may be hinged together on lines parallel with the line of draft.

My invention consists in the construction, arrangement and combination of elements hereinafter set forth, pointed out in my claims and illustrated by the accompanying drawing, in which—

Figure 1 is a plan and Fig. 2 a rear elevation of my improved drag. Fig. 3 is a cross-section on the line 3—3, Fig. 4 a cross-section on the line 4—4 and Fig. 5 a longitudinal detail section on the line 5—5 of Fig. 1, on an enlarged scale and with the derrick devices omitted.

In the construction of the device as shown two main drag sections are employed, designated generally by the numerals 10, 11. Each main drag section 10, 11 is formed of angle iron blades or drag members 12, 13, 14, 15, 16, in this instance five in number,

and said angle iron blades are inclined and converge at their rear end portions toward the median line of the device, which is designed to be substantially in the middle of the crown of a road being worked when in use. In this manner the angle iron blades of the two main drag sections are oppositely arranged, said main drag sections being on opposite sides of the median line of the device. The angle iron blades 12, 13, 14, 15, 16 are of varying lengths, the members 13, 14, 15 and 16, the only ones which extend to the front end of the machine, being connected by a transversely arranged front cross bar 17 mounted upon and suitably connected to the horizontal flanges of said blades as by bolts 18. Similarly the rear ends of the blades 12, 13, 14, which are the only ones that extend entirely to the rear end of the machine, are connected by a rear cross bar 19. An intermediate cross bar 20 connects the forward end of the blade member 12 to the rear end of the blade member 15 and extends across and is connected to intermediate portions of the blade members 13, 14, said cross bar 20 preferably being substantially parallel with the front and rear cross bars and at right angles to the line of draft. Another intermediate cross bar 21 is employed forwardly of the cross bar 20 and is connected to the rear end of the inner blade member 16 and crosses and is connected to intermediate portions of the blade members 13, 14, 15, and projects at its outer end laterally beyond the member 13 substantially to a right line intersecting end portions of the front and rear cross members. It will be seen, then, that the blade members 13, 14 are the only ones which extend from front to rear of the machine, that the outermost blade 12 and innermost blade 16 are relatively short, and that the blade 15 is of a length between that of the members 13—14 and 12—16. Thus, while the longitudinal members of the main drag sections (that is the angle iron blades) are arranged obliquely, yet the general outlines of each of said sections is that of a rectangle in plan, such rectangle being defined by the front and rear cross members and imaginary lines connecting their ends, the outside longitudinal members being of shorter length than the intermediate ones so as not to project much if any beyond the outlines of the rectangle defined. The cross members 17, 19, 20 and 21 preferably are

formed of channel bars arranged with their channels directed upwardly. Brace members 22 are provided and are inclined oppositely to the longitudinal blade members 5 and extend from the forward inner corner to the rear outer corner of each main drag section. The braces 22 preferably are of strap metal and pass above and are connected to each of the blades 12, 13, 14, 15, 10 16 and beneath the cross bars 17, 21, 20 and 19, being bent or curved to pass beneath said cross members.

Supplementary drag sections 23, 24 are employed, one outside of each of the main 15 drag sections and connected thereto as hereinafter described, and said supplementary sections are formed each with a long outer angle iron blade 25 and a short inner angle iron blade 26. The blades 25, 26 are inclined 20 at their rear ends inwardly toward the median line of the device and are substantially parallel with the blades of the adjacent drag sections. The short blade 26 of each supplemental drag section is in line with the short 25 outer blade 12 of the adjacent main section. The forward ends of the blades 25, 26 are connected by a front cross bar 27 and a short cross bar 28 is mounted across and projects at each end somewhat beyond the rear end of 30 the longer blade 25, the supplemental sections being of considerably less width at their rear than at their forward ends. An intermediate cross bar 29 is mounted across an intermediate portion of the longer blade 35 25 and across and adjacent the rear end of the shorter blade 26, and said intermediate cross bar is substantially in alignment with the intermediate cross bar 21 of the adjacent main drag section. An inclined flat brace 30 connects the inner end of the front cross bar 27 to the outer end of the rear cross bar 28 and crosses and is connected to the blade 26, the intermediate cross bar 29 and the blade 25 in sequence. Hinge members 31, 32, 33 40 are fixed to inner ends of the cross bars 27, 29 and 28 respectively of the supplemental drag sections and project within outer end portions of the cross bars 17, 21 and 19 respectively of the adjacent main drag sections, and are connected pivotally to the latter members by hinge bolts 34. The hinge members 31, 32, 33 preferably are formed of metal straps mounted within the channels of the cross bars 27, 29 and 28 and formed with 45 eyes within the channels 17, 21, and 19, through which eyes the hinge bolts pass loosely. Thus the supplemental sections 23, 24 are pivotally connected to outer margins of the main sections 10, 11 respectively, the 50 three hinges 31, 32, 33 on each side being in longitudinal alignment and parallel or substantially parallel with the line of draft of the machine.

Wing sections 35, 36 are provided, one outside of and pivotally connected to each of

the supplemental sections 23, 24. Each wing section is provided with a single angle iron blade 37 extending from front to rear end thereof and inclined preferably to a greater extent than the inclination of the blades of 70 the main and supplemental drag sections. The wing sections 35, 36 also are of considerably greater width at their forward than at their rear ends, the front ends of the blades 37 being connected to outer ends of forward 75 cross bars 38, which cross bars are extended inwardly a considerable distance from said blades and pivotally connected by hinges 39 to outer ends of the cross bars 27 of the adjacent supplemental sections. Short rear 80 cross bars 40 cross and are fixed to and project slightly in both directions beyond rear ends of the blades 37 and are pivotally connected to outer ends of the cross bars 28 of the supplemental drag sections by hinges 41. 85 An intermediate cross bar 42 is fixed to and projects inwardly from the blade 37 and is pivotally connected to the outer end of a cross bar 29 of a supplemental section by a hinge 43. A flat inclined brace 44 is fixed to 90 the inner end of the forward cross bar, crosses and is fixed to the inner portion of the intermediate cross bar 42 and the rear portion of the blade 37, and is connected at its rear end to the outer end of the short rear 95 cross bar 40.

Eyes 45 are fixed to outer end portions of the front cross bars 17 of the main sections and clevises 46 engage said eyes and are removably secured to end portions of a draft beam 47. Other clevises 48 are secured to the draft beam 47, conjunctively with the clevises 46 but on the forward side of said beam, and any suitable draft means may be attached to said clevises 48 for advancing 105 the device.

In Figs. 1 and 2 I have shown means to facilitate folding of the outer sections of the device upon the main sections at times, either for transportation, for crossing of bridges, 110 or to permit the passage of traffic. A derrick 49 is formed of channel iron bent at its center, arranged in upright position transversely of the device, and having end portions of its legs secured pivotally to outer 115 marginal portions of the main drag sections 10, 11. A brace rod 50 is pivotally connected at one end to the top of the derrick bar 49 and extends forwardly and downwardly and has its lower end pivotally connected to one 120 of the main drag sections adjacent the median line of the device. A winch 51 is carried by each leg of the derrick bar 49 at a suitable altitude and a cable 52 is provided therefor and passes over a pulley block 53 detachably secured to the outer margin of another drag section, such as a wing section 125 35 or 36. The cable 52 then passes over a fixed pulley block 54 carried by the upper part of the derrick, and back to attachment 130

to the first pulley block. It is to be understood, however, that any other suitable arrangement of block and tackle devices may be provided. A ratchet 55 is fixed to the 5 winch 51 and is adapted to be engaged by a pawl 56 pivoted to the derrick bar. This device may be employed to facilitate folding of the outer sections inwardly and upon the inner sections as desired.

10 The main drag sections 10, 11 are hinged together by hinges 57, connecting adjacent ends of the respective front cross bars 17, and 58, connecting adjacent ends of the respective rear cross bars 19.

15 It is to be understood that some of the sections, as for instance the supplemental sections 23, 24, may be disconnected and the device used without them at times if desired.

In use the drag constructed as shown and 20 described is employed particularly where it is desired to treat the entire width of the roadway at a single operation, as may be done where traffic is slight. The device is moved along with the main drag sections 25 10, 11 traveling on opposite sides of the center of the roadway and making the crown thereof, and the supplemental sections outside of said main sections and supplementing them in treating the main 30 road surface, while the wing sections may travel on and treat the berm, the blades 37 of said wing sections, with their greater inclination, cutting grass and weeds and comminuting them and passing them to the center of the roadway. The hinging of the sections on longitudinal lines permits the drag to conform to the transverse contour of the roadway, as well as the folding of the outer sections inwardly upon the others when it is 35 desired to permit passage of traffic or to transport the device over bridges and the like.

Attention is called to the arrangement of the inclined blades of the main drag sections, the outermost of said blades being of 40 less length than the intermediate and not extending outside of the outlines of the sections of which they are part; and the co-acting arrangement of the innermost inclined blades of the supplemental drag sections, arranged in a similar manner, so that 45 said main and supplemental sections may be hinged on lines parallel or substantially parallel with the line of draft.

50 55 I claim as my invention—

1. A drag section, comprising front and rear cross bars, inclined blades spaced apart, some of said blades being connected at their forward ends to said front cross bar and 55 some connected at their rear ends to the rear cross bar, some of the blades extending from front to rear of the section and being connected to both of said cross bars, the outermost of the inclined blades being of 60 less length than the intermediate blades and

not extended appreciably beyond right lines connecting end portions of the front and rear cross bars, one of the intermediate blades being shorter than the others but longer than the outermost blades, and spaced 70 intermediate cross bars crossing and connected to intermediate portions of the longer blades and each connected at one end to an end portion of one of the short blades, one of said intermediate cross bars also being connected at one end to an end portion of the shorter of the intermediate blades. 75

2. A drag section, comprising front and rear cross bars, inclined blades spaced apart, 80 some of said blades being connected at their forward ends to said front cross bar and some connected at their rear ends to the rear cross bar, the outermost of said blades being of less length than the intermediate blades and not extended appreciably beyond 85 right lines connecting end portions of the front and rear cross bars, intermediate cross bars crossing and connected to intermediate portions of the intermediate blades and connected to end portions of the short outer 90 blades, and a brace inclined in the opposite direction to the inclination of said blades and crossing and connected to said blades.

3. In a road drag having a main drag section and draft means attached thereto, 95 the combination with said main drag section of a supplementary drag section comprising front, intermediate and rear cross bars adapted to be hingedly secured at their inner ends to said main drag section, said cross bars being of progressively increasing length, a scraper blade arranged at oblique angles to said cross bars and secured thereto near their outer ends, and a second scraper blade substantially parallel with the 100 first and of shorter length, the latter scraper blade being attached to and near the inner ends of the intermediate and rear cross bars. 105

4. A drag section, comprising front and rear cross bars, blades spaced apart and arranged obliquely relative to said cross bars and to the line of draft, some of said blades being of greater length than the others and connected to both the front and rear cross bars, the shorter of said blades being arranged at marginal portions of the drag section and connected to only one of said cross bars, an intermediate cross bar connected to intermediate portions of the longer of 110 said blades and to end portions of the 115 shorter of said blades, and a brace obliquely arranged and connected to said front and rear cross bars and crossing and connected to said blades.

5. In a drag, separate drag sections each 120 formed with front and rear cross bars and inclined blades connected thereto, and hinge connections between the respective cross bars of said drag sections, the blades of both sections being inclined in the same direction 125 130

and the blades on adjacent sides of each of said sections being foreshortened and opposed to each other and together extending from front to rear of the device when the sections are hinged together, each section also being provided with an intermediate cross bar connected to its longer blades and connected to and supporting the shortened

end of its shorter blade, the hinge connections between the sections being substantially parallel with the line of draft.

Signed at Pocahontas, in the county of Pocahontas and State of Iowa, this fifth day of March, 1918.

JOHN L. PASCAL.
